US00D531123S

(12) **United States Design Patent** (10) **Patent No.:** **US D531,123 S**
Hu et al. (45) **Date of Patent:** **** Oct. 31, 2006**

(54) **USB CONNECTOR**

(75) Inventors: **Jin-Kui Hu**, Kunshan (CN); **Guo-Hua Zhang**, Kunshan (CN); **Zi-Qiang Zhu**, Kunshan (CN)

(73) Assignee: **Hon Hai Precision Ind. Co., Ltd.**, Taipei Hsien (TW)

(**) Term: **14 Years**

(21) Appl. No.: **29/232,533**

(22) Filed: **Jun. 20, 2005**

(30) **Foreign Application Priority Data**

Dec. 20, 2004 (CN) 2004300551798

(51) **LOC (8) Cl.** **13-03**

(52) **U.S. Cl.** **D13/147**

(58) **Field of Classification Search** D13/133, D13/146–147, 154, 184, 199; D14/356, 363, D14/365, 385, 433; 439/350, 607–610, 677, 439/680–682

See application file for complete search history.

(57) **CLAIM**

The ornamental design for a USB connector, as shown.

DESCRIPTION

FIG. 1 is a perspective view of a USB connector showing our new design;

FIG. 2 is a front elevational view of FIG. 1;

FIG. 3 is a rear elevational view of FIG. 1;

FIG. 4 is a left side elevational view of FIG. 1;

FIG. 5 is a right side elevational view of FIG. 1;

FIG. 6 is a top plan view of FIG. 1; and,

FIG. 7 is a bottom plan view of FIG. 1.

1 Claim, 6 Drawing Sheets

FIG. 1

FIG. 2

FIG. 3

FIG. 4

FIG. 5

FIG. 6

FIG. 7
